UNITED STATES PATENT OFFICE.

J. HARMAN HOOVER, OF ASHLAND, PENNSYLVANIA.

MILK-CAN.

SPECIFICATION forming part of Letters Patent No. 307,947, dated November 11, 1884.

Application filed August 7, 1884. (No model.)

To all whom it may concern:

Be it known that I, J. HARMAN HOOVER, a citizen of the United States, and a resident of Ashland, Schuylkill county, Pennsylvania, have invented certain Improvements in Milk-Cans, of which the following is a specification.

The object of my invention is to so construct a milk-can top and lid as to prevent the splashing of the milk and loss of the same by leakage between the can and the lid. This object I attain in the manner hereinafter set forth, reference being had to the accompanying drawings, in which—

Figure 1 is a sectional view of a milk-can top and lid with my improvements, and Fig. 2 a view of a modified form of the same.

A is the body of the can, and B the upper portion or neck of the same, which has some distance below the mouth a contracted portion, *a*, to which fits snugly a central cylindrical projection, *b*, on the lid D, the latter having an annular downwardly-projecting flange, *f*, which fits closely to the upper vertical portion of the neck of the can, and rests upon an internal rib, *g*, in the neck, as shown in Fig. 1, the use of this rib not being essential, however, as the lower edge of the flange may, if desired, be brought into contact with the contraction *a* of the neck, as shown in Fig. 2. The close joint between the contracted neck and the projection *b* of the lid prevents the splashing of the milk into violent contact with the lid when the can is roughly handled, and even if a portion of the milk finds its way

into that portion of the neck above the contraction *a* this milk is prevented from escaping by reason of the close fit of the flange *f* of the lid to the vertical portion of the neck of the can, and, in the case of the can shown in Fig. 1, to the rib *g*. The flange *f* thus becomes 40 of importance to the combination, for the lid may be loosened by the constant and forcible splashing of the milk against the projection *b*, so that, in the absence of the flange, the milk which entered the upper portion of the 45 neck might escape between the lid and the mouth of the can.

I therefore claim as my invention—

1. The combination of the can, having a neck with upper vertical portion and a contraction, *a*, below the same, with the lid having a central projection, *b*, fitting snugly to the contraction *a*, and a flange, *f*, fitting closely to the vertical portion of the neck, as set forth.

2. The combination of the can, having a neck with upper vertical portion and the internal rib, *g*, and contraction *a* below the same, with the lid having a central projection, *b*, fitting snugly to the contraction *a*, and a flange, *f*, fitting closely to the vertical portion of the neck and seated upon the rib *g*, as set forth.

In testimony whereof I have signed my name to this specification in the presence of two subscribing witnesses.

J. HARMAN HOOVER.
